PHASE MODULATION

Murray G. Crosby, Riverhead, N. Y., assignor to
Radio Corporation of America, a corporation of
Delaware

Application July 26, 1940, Serial No. 347,587

4 Claims. (Cl. 179—171.5)

This application concerns a new and improved phase modulation means of the type wherein an element of a phase shifter is varied in value to produce a variable phase shift and consequently produce phase modulation. A phase shifter utilizing inductance and resistance is employed so that the resistance may take the form of a tube plate resistance which may be modulated in accordance with the signal voltage. Phase modulation has been accomplished heretofore by controlling the value of a circuit element at signal frequency to thereby control the phase of current therein. In my system I use a mid-tapped inductance and a resistance and vary the resistance. My circuit will produce a greater phase shift for a given amount of resistance variation than certain known systems of this nature. My system also makes a greater range of total phase variation possible. One of its most outstanding advantages is the fact that the phase shift is accomplished without amplitude change. This means that the phase modulation will not be accompanied by concomitant amplitude modulation which must be limited off by means of a limiter following the modulator stage.

In describing my invention, reference will be made to the attached drawing wherein:

Figs. 1 and 2 each show a modification of a phase modulator arranged in accordance with my invention; while

Fig. 3 illustrates the essential elements of the phase shifter and is used with the vector diagrams of Fig. 4 to illustrate the operation of my system.

In the phase modulator of this disclosure a phase shifter such as shown in Fig. 3 is utilized. This phase shifter shifts the phase of voltage E_1 by an amount depending upon the magnitude of the reactances of L_1 and L_2 and resistance R . The vector diagram of this type of phase shifter is shown in Fig. 4. The voltage to be phase-shifted is applied as E_1 . E_1 causes a current to flow through L_1 and R so that a reactance drop XL_1I will appear across points O—A of Fig. 3 and a resistance drop RI will appear across terminals O—C of Fig. 3. A reactance drop XmI will appear across terminals O—B of Fig. 3 by virtue of the mutual inductive coupling which exists between L_1 and L_2 . Voltage E_1 is the resultant of the reactance and resistance drops XL_1I and RI . The output voltage of the phase shifter E_2 is the resultant of the mutual reactance drop XmI and the resistive drop RI . It can be seen that E_1 is different in phase by an amount θ depending upon the relative values of the resistive voltage drop RI and the reactive voltage

drops XL_1I and XmI . Consequently, by varying the value of R , the phase may be varied between zero and almost 180 degrees.

From the vector diagram of Fig. 4, it can be seen that as R is varied between zero and a value equal to the reactive impedance, the phase shift, θ , will be varied between zero and 90 degrees and the amplitude of the output voltage, E_2 , will not vary since E_2 is always equal to E_1 so that there is no variation of the attenuation with modulation. Consequently, phase modulation is possible without the introduction of concomitant amplitude modulation.

The phase shifter of Fig. 3 is adapted to use as a phase modulator by utilizing a resistance at R which can be controlled at a modulation potential rate. If the phase of the current is to be keyed or modulated, the value of the resistance R may be varied by keying signals which shunt a portion of R or all of R by a second resistance to change its value in accordance with the signal. In a preferred embodiment the resistance R is comprised of the resistance of a vacuum tube as illustrated in Figs. 1 and 2. Hence, by applying modulating potentials to the grid of the vacuum tube, the phase of the voltage transmitted through the phase shifter is varied in accordance with the modulating potentials since, as is well known, the plate resistance of a vacuum tube may be varied by varying the grid potential. Circuits having these features are shown in Figs. 1 and 2.

In the circuit of Fig. 1 constant carrier energy is supplied from source 10 by transformer 12 to the grid 14 of amplifier 20. The output circuit connected with the anode 22 of the amplifier tube 20 comprises a tuned circuit 4 wherein the amplified wave appears, and from which it is fed to the phase shifter consisting of inductance 26 and the resistance between the plate 30 and cathode 34 of tube 36. The phase-controlled output of the phase shifter is fed to the control grid 40 of the amplifier tube 42 and thence to tuned circuit 44. Energy from tuned circuit 44 is fed to power amplifier 48 and antenna 9. Power amplifier 48 may contain frequency multipliers and limiters as is known to the art of phase modulation.

Modulating potentials are applied to jack 31 and then through transformer 32 to the grid 35 of tube 36. Bias is furnished to the grid 35 of tube 36 by means of battery 37.

It is well known that the variation of the grid voltage on a tube varies its plate resistance. Consequently, the application of modulating potentials to the grid 35 of tube 36 will vary the plate resistance of tube 36 and, in turn, vary the phase

shift produced by the phase shifter. This produces a phase modulation of the energy from carrier source 1.

In the circuit of Fig. 2 the resistance between the anode 50 and cathode 52 of a diode tube 54 is used for the variable resistance of the phase shifter. This diode resistance is varied by applying the modulating potentials through jack 31, transformer 32 and the radio-frequency choke RFC. Condenser 58 is a blocking condenser to keep the plate voltage from amplifier tube 20 from being applied to diode 54. Battery 57 biases the diode to a mid-position on its resistance-voltage characteristic so that the diode resistance may be modulated at a higher or lower value than this mid-position value. It can be easily seen how the elements of the circuit of Fig. 2 can be substituted for the corresponding elements of Fig. 1, and further description of this modification is believed unnecessary.

When the frequency of the carrier to be phase modulated is high, so that the plate capacity of tube 36 becomes a low-impedance shunt in comparison to the plate resistance, tuned circuit TC may be added to tune out the capacity. This tuned circuit is tuned to the carrier frequency so as to be resistive to that frequency. TC is added by closing switches S and S1.

As described in my United States application Serial No. 36,473 filed August 16, 1935, now United States Patent #2,104,318 issued January 4, 1938, several of these phase modulators may be cascaded in order to produce an increased or more faithful degree of phase modulation.

What is claimed is:

1. Means for shifting the phase of alternating current including an inductance, a variable resistance having one terminal connected to a point on said inductance and a second terminal connected to a point of low alternating current voltage, said variable resistance having inherent reactance, connections for impressing voltages the phase of which is to be shifted on said inductance and resistance, connections for deriving voltages, the phase of which may be varied by varying the value of said resistance, from said inductance and resistance, and connections including the inherent reactance of said resistance in a circuit parallel tuned to the frequency of said voltages.

2. In a phase modulation system a source of wave energy the phase of which is to be modulated in accordance with control potentials, an

5 inductance, a variable impedance having one terminal coupled to a point on said inductance and a second terminal coupled to ground or equivalent potential, said impedance having inherent reactance, a circuit coupling said source to one terminal of said inductance and to said second terminal of said impedance, connections for deriving phase shifted current from said inductance and said impedance, a control circuit for varying the value of said variable impedance in accordance with said control potentials, and connections including the inherent reactance of said impedance in a circuit parallel tuned to the frequency of said wave energy.

10 3. In a phase modulation system, a source of wave energy the phase of which is to be modulated in accordance with modulating potentials, an inductance, an electron discharge device having an anode, a cathode and a control grid, a connection between the anode of said device and a point on said inductance, means for impressing wave energy from said source between a second point on said inductance and the cathode of said device, means for deriving phase modulated wave energy from a third point on said inductance and the cathode of said device, a source of modulating potentials, means for impressing modulating potentials from said source on the control electrode and cathode of said device, and 15 a circuit tuned to the frequency of said wave energy connected between the anode and cathode of said device.

20 4. In a wave length modulation system, a source of alternating current the wave length 25 of which is to be modulated, a source of modulating potentials, an inductance, an electron discharge device having an anode electrode and a cathode electrode, said device having inherent reactance which appears between said electrodes, 30 a lead coupling one of said electrodes to a point on said inductance, couplings for impressing current from said source to be modulated on said inductance and the other electrode of said device, a circuit for modulating the impedance of 35 said device in accordance with modulating potentials from said source, connections for deriving modulated current from said inductance and said other electrode of said device, and connections including the reactance inherent in said device between its anode and cathode in a circuit parallel tuned to the frequency of the current of said source of current.
